UNITED STATES PATENT OFFICE.

HARRY McBRIDE SMURR, OF ARMONA, CALIFORNIA.

TOY AEROPLANE.

1,397,989.

Specification of Letters Patent. Patented Nov. 22, 1921.

Application filed July 15, 1920. Serial No. 396,384.

To all whom it may concern:

Be it known that I, HARRY M. SMURR, a citizen of the United States, residing at Armona, in the county of Kings and State 5 of California, have invented certain new and useful Improvements in Toy Aeroplanes, of which the following is a specification.

This invention relates to a toy aeroplane 10 which is capable of being manually propelled over the ground.

An important object of the invention is the provision of a toy aeroplane of the conventional aeroplane construction, which is 15 capable of being manually propelled over the ground, and in which the propeller blade is made to revolve.

A further object of the invention is the provision of a toy aeroplane of the above described character having means thereon to make a noise simulating the explosions of 20 an aeroplane engine.

A further object of the invention is the provision of a device of the above character 25 being so adjustable as to permit persons of varying sizes to propel the same.

In the accompanying drawings forming a part of this specification and in which like reference characters designate like parts 30 throughout the same:

Figure 1 is a side elevation of the toy aeroplane.

Fig. 2 is a plan view of the toy aeroplane.

Fig. 3 is a front elevation of the toy aeroplane.

Fig. 4 is a side elevation partly in section of the toy aeroplane.

Fig. 5 is a fragmentary sectional view 40 showing the means employed for making a noise similar to the explosions of an aeroplane engine.

Fig. 6 is a front sectional view of the supporting means.

Fig. 7 is a perspective view of the empennage or rudder of the toy aeroplane.

In the drawings, wherein for the purpose 50 of illustration is shown a preferred embodiment of my invention, the letter A represents the fuselage having wings B thereon,

to which an empennage or rudder C is pivotally attached. The fuselage A rotatably carries the propeller blade D and has a landing gear constructed thereon comprising an under frame E and supporting wheel F to 55 which is attached an adjustable handle G for manually propelling the aeroplane.

The fuselage A is preferably constructed of hard wood and is of conventional aeroplane construction, being gradually tapered from the front toward the rear. A longitudinal recess 10 is provided in the fuselage 60 A and communicates through an aperture 11 with the outside and beneath the fuselage.

The aeroplane is preferably of bi-plane 65 construction, and has a bottom wing 12 mounted upon the forward part of the fuselage A, and overhanging which is the wing 13 supported by struts 14 to the lower plane 12 and which plane is slightly longer on 70 each end than the lower plane 12.

The empennage or rudder C is pivotally mounted upon the rear of the fuselage A by a pin 15 and comprises a horizontally pointed portion 16 and the vertical rudder 75 portion 17. The portion 17 is provided with slits 18 stamped or cut therein and which are provided for the purpose of receiving the pin 15.

The propeller D is preferably of the screw 80 type having blades 19 and 20 thereon and which is mounted upon a shaft 21 projecting within the fuselage and bearing therein, and which has a portion thereof projecting within the longitudinal recess 10 of the fuselage. 85 A plate 22 is provided upon the nose of the fuselage and maintained in position by rivets 23 for the purpose of maintaining the shaft within the fuselage or body A.

The under frame E of the toy aeroplane 90 is preferably composed of the two longitudinal members 24 and 25 which are rigidly connected to the rear of the fuselage by the braces 26 and 27 respectively, and which are connected to the forward end of the 95 fuselage A by braces 28 and 29 respectively, rigidly attached to the wing 12 by rivets 30 or the like. A bolt 31 is provided through the forward part of the longitudinal members 24 and 25 and the lower part of the 100

- braces 28 and 29, and which acts as an axle for rotatably supporting the wheel F. The wheel F is preferably of disk construction having a solid tire 32 thereon, and which 5 has preferably integral therewith a grooved hub 33 and a toothed hub 34 disposed upon the side opposite the grooved hub 33. If it is preferred the hub sections 33 and 34 can be made separate from the wheel structure 10 F and rigidly assembled thereto during the assemblage of the device. A flexible cable 35 is provided which engages the groove 36 of the grooved hub 33 and which is projected upwardly in the aperture 11 in the 15 fuselage A and placed about the propeller shaft 21 for turning the propeller upon rotation of the wheel F. The longitudinal member 25 of the undercarriage E has a portion thereof adjacent its connection to the 20 bolt 31 cut away and is provided with the groove 37 adapted for the reception of an end 38 of a flexible strip 39, of sufficient length to engage the teeth 40 of the toothed wheel 34.
- 25 The handle G is provided with the hand engaging portion 41 having the aperture 42 therein adapted for reception of a string, rope, stick or the like, and which also has an end 42 thereof pivotally connected to 30 the longitudinal members 24 and 25 by a bolt 43 which also engages the depending ends of the braces 26 and 27.
- In operation, the handle G can be adjusted upon the bolt 43 in order that the 35 end of the handle engaging portion 41 can be adjusted to the required height, and is then tightened in its place by rotation or tightening of the nut 44 upon the bolt 43. In its downmost position the portion 42 of 40 the handle G abuts against a bolt 45, and is prevented from any further downward movement. As the toy aeroplane is manually propelled over the ground, the rotation of wheel F will also rotate the grooved hub 45 33 and toothed hub 34. As the toothed hub 34 rotates the teeth 40 will push against the flexible strip 39 until the strip comes in contact with the outwardly flaring face 47 of the groove 37, thus bending the strip and 50 putting it under pressure and when this tooth 40 releases the flexible stick 39 it will fly back into its original position and strike against the succeeding tooth 40, thus making noises in rapid succession which simulate 55 late the explosion of an aeroplane engine. As the hub 33 also revolves with the wheel F it will cause the flexible cable 35 to rotate the shaft 21 which is transmitted to the propeller D and consequently causes the propeller D to rotate while the wheel F is rotating and with a great many more revolutions in a certain period of time than the wheel. Since the empennage C is pivotally mounted upon the rear of the fuselage the 60 65 rudder member 17 will because of the con-

tact with the air and the resistance thereof point in the direction in which the toy aeroplane is moving.

It is to be understood that the form of my invention herewith shown and described is 70 to be taken as a preferred example of the same and that various changes in the shape, size and arrangement of parts may be resorted to without departing from the spirit 75 of the invention or the scope of the subjoined claims.

I claim:

1. In a toy, the combination of wings, a fuselage connected to said wings, a propeller rotatably carried by said fuselage, a landing gear including an under frame, a wheel detachably mounted upon said frame, means disposed upon one side of said wheel for simulating the explosions of an internal combustion engine, means disposed upon 85 the opposite side of the wheel for driving said propeller, and a handle structure detachably and adjustably connected to said landing gear for propelling said toy.

2. In a toy aeroplane, the combination of 90 a body resembling the fuselage of an aeroplane and having a recessed portion therein, a shaft rotatably mounted upon said fuselage and having a portion thereof in the recess therein, a propeller upon said shaft, an 95 empennage upon said fuselage pivoted to point in the direction of motion of the toy, an underframe having an axle therein, a supporting wheel bearing upon said axle having a grooved hub on one side and a 10 toothed hub upon the other side thereof, a flexible cable connecting the grooved hub and propeller shaft whereby the propeller is rotated upon rotation of the wheel, and a flexible strip in said underframe engaging 10 said toothed hub and adapted to ride thereupon for making a noise resembling an aeroplane engine upon rotation of the supporting wheel, and an adjustable handle pivotally mounted upon said handle frame for 11 manually propelling the toy.

3. In a toy, the combination of an aeroplane structure, of a handle adjustably connected thereto for manually operating the toy, and means for limiting downward movement of said handle with respect to said aeroplane structure.

4. In a toy aeroplane, the combination of 1 a fuselage, planes, landing gear including a pair of longitudinal members, means for detachably bracing said members forwardly to said aeroplane, means for detachably bracing the members rearwardly to the fuselage, and a wheel detachably connected to 1 said members.

5. In a toy aeroplane, the combination of a fuselage, a wing, an under frame construction including a pair of longitudinal members, braces rearwardly upon said fuselage, a bolt for connecting said braces to said 1

longitudinal members, braces forwardly of said aeroplane structure upon said wing, a bolt for connecting said forward braces to said longitudinal members, and a wheel 5 mounted upon said last mentioned bolt.

6. In a toy aeroplane, the combination of a fuselage, a wing, an under frame construction including a pair of longitudinal mem-

bers, braces rearwardly upon said fuselage, a bolt for connecting said braces to said longitudinal members, a wheel, means for attaching said wheel to said members, and a handle adjustably connected to said bolts for manually propelling the aeroplane structure.

HARRY McBRIDE SMURR.
